C. E. LONDON
APPARATUS FOR SALVAGING SUNKEN VESSELS.
APPLICATION FILED OCT. 15, 1918.

1,296,983.

Patented Mar. 11, 1919.

UNITED STATES PATENT OFFICE.

CHARLES E. LONDON, OF STEVESTON, BRITISH COLUMBIA, CANADA.

APPARATUS FOR SALVAGING SUNKEN VESSELS.

1,296,983.

Specification of Letters Patent.

Patented Mar. 11, 1919.

Application filed October 15, 1918. Serial No. 258,214.

To all whom it may concern:

Be it known that I, CHARLES E. LONDON, a subject of the King of Great Britain, and a resident of Steveston, in the Province of 5 British Columbia, Canada, have invented certain new and useful Improvements in Apparatus for Salvaging Sunken Vessels, of which the following is a specification.

My invention relates to improvements in 10 the salvaging of sunken vessels, including those sunk in a depth in which it is not possible or feasible for a diver to operate, and the object of my invention is to devise an apparatus by means of which the lifting 15 cables are permanently secured to the vessel in a highly practical manner so as to sink with it and are capable of being thereafter raised to the surface so that a hold may be obtained at once by the lifting medium 20 without the necessity of any intermediate operations, the cables being provided with means operative on the sinking of the vessel adapted to float to the surface and indicate the position of the wreck.

25 I attain this object by the means illustrated in the accompanying drawings in which—

Figure 1 is a transverse section of a floating hull illustrating the arrangement of my 30 apparatus.

Fig. 2 is a transverse section of a sunken hull showing the lifting cables ready for attachment to the lifting medium.

Fig. 3 is a detail view of the cable reel and 35 lifting wheel.

Fig. 4 is a perspective view of the reel flange and trunnion.

Fig. 5 is a detail view in perspective of a 40 spring cable guide.

Fig. 6 is a view illustrating the roller bearing for the lifting wheel.

Fig. 7 is a cross section through the runway.

Similar figures of reference indicate similar parts throughout the several views.

1 indicates the hull of a vessel in which are built pairs of strong runways 2, as indicated in Figs. 1 and 2, the upper ends of the runways curving outwardly and terminating 50 close to the sides of the vessel under the deck. There may be any number of pairs of such runways according to the size of the vessel, the respective pairs being located at spaced intervals throughout the vessel's 55 length, and adjacent each runway is positioned a reel, indicated by the numeral 3,

rotatably mounted in suitable bearings 4 and 5 rigidly secured to the hull and adapted to carry sufficient length of lifting cable 6 as will reach the surface when unwound after 60 the sinking of the vessel, and in addition to the lifting cable 6 the reel also carries wound thereon and attached to the free end of the cable 6 a small cable 7 to the free end of which is attached a buoy 8, carried on the 65 deck, the free end of this cable being passed through guides 9 secured to the bulkhead or any other suitable part of the hull, these guides being divided so that their divided ends may spring apart to release the cable 6, 70 as hereinafter described.

The lower end of the main cable 6 passes over the flange 10 of the reel and down the face of it, the cable being laid in a groove 11 formed in the flange so that it will lie 75 flush with the surface thereof and then carried along a groove 12 formed in the reel trunnion 13 so that it may be connected by a swivel 14 to a lifting wheel 15 of great strength mounted in the runway, which 80 wheel may be supported by a suitable roller bearing 16, if preferred, as indicated in Fig. 6. The cable 6 is held in place on the reel flange and trunnion by means of spring fingers 17 capable of opening outwardly, however, under strain, to permit the release of 85 the rope.

The manner in which the invention operates will be apparent as it will be seen that on the sinking of the vessel, the buoys will 90 float to the surface carrying the cables 7 up with them, the floating buoys indicating the position of the wreck. When it is desired to raise the vessel the lifting cables 6 are then hauled to the surface by means of the 95 smaller ones 7, this action causing the reels 3 to rotate to unwind the cables until, when the cable on each reel is all unwound, the strain thereon causes the spring fingers 17 and guides 9 to spread apart, thus freeing 100 the cable from the reel and allowing the lifting wheel 15 to be carried up to the top of the runway, after which the vessel may be raised by continued lifting strain on the cables.

105 What I claim as my invention is:

1. Apparatus for raising sunken vessels, comprising lifting cables secured to the vessel and means for enabling the free end of each cable to be raised to the surface after 110 sinking, said means being adapted to permit travel of the secured end of the cable

from its normal point of attachment to a predetermined lifting point.

2. Apparatus for raising sunken vessels, comprising rotatably mounted reels secured 5 transversely to the vessel at suitable points, a lifting cable normally wound on each reel having its lower end rotatably connected to the vessel's structure and capable of limited vertical movement under strain and having 10 secured to its free end a smaller cable also wound on the reel, said smaller cable being provided on its free end with a buoy of sufficient buoyancy to unwind the small cable off the reel as the vessel sinks.

15 3. Apparatus for raising sunken vessels, comprising outwardly curving runways the lower ends of which are secured to the vessel at suitable points on each side of the longitudinal center line and terminating at 20 their upper ends close to the vessel's side, a lifting wheel rotatably mounted in each runway and normally supported in the lower end of the same, rotatably mounted reels secured to the vessel adjacent the respective 25 runways, a lifting cable normally wound on each reel having its lower end connected to its respective lifting wheel and having attached to its free end a smaller cable also normally wound on the reel, the said smaller 30 cable being provided at its free end with a buoy of sufficient buoyancy to unwind the small cable off the reel as the vessel sinks.

4. Apparatus for raising sunken vessels, comprising a plurality of suitably located 35 flanged cable reels having trunnions by which they are rotatably mounted in bearings secured to the vessel, each said reel having a groove cut in the periphery of its outer flange extending down the face thereof and continued through the outer trunnion, a lifting cable normally wound on each reel having its lower end passed through 40 said groove, means for retaining said cable in the groove during rotation of the reel, and means for rotatably connecting the lower end of the cable to the vessel's structure.

5. Apparatus for raising sunken vessels, comprising a plurality of suitably located 50 flanged cable reels having trunnions by which they are rotatably mounted in bearings secured to the vessel, each said reel having a groove cut in the periphery of its outer flange extending down the face thereof and continued through the outer trun- 55

nion, a lifting cable normally wound on each reel having its lower end passed through said groove, means for retaining the said cable in the groove during rotation of the reel, means for rotatably connecting the lower end of the cable to the vessel's structure, and means operative on the vessel's sinking for enabling a grip on the sunken cables to be obtained. 60

6. Apparatus for raising sunken vessels, 65 comprising a plurality of suitably located flanged cable reels having trunnions by which they are rotatably mounted in bearings secured to the vessel, each said reel having a groove cut in the periphery of its 70 outer flange extending down the face thereof and continued through the outer trunnion, a lifting cable normally wound on each reel having its lower end passed through said groove, spring fingers secured to the 75 flange and the trunnion to retain the cable in the said groove during rotation of the reel and adapted to be spread under strain to free the cable from the reel, means for rotatably connecting the lower end of the 80 cable to the vessel's structure, and means operative on the vessel's sinking for enabling a grip on the sunken cables to be obtained.

7. Apparatus for raising sunken vessels, 85 comprising a plurality of suitably located flanged cable reels having trunnions by which they are rotatably mounted in bearings secured to the vessel, each said reel having a groove cut in the periphery of its 90 outer flange extending down the face thereof and continued through the outer trunnion, a lifting cable normally wound on each reel having its lower end passed through said groove, an outwardly curving runway 95 adjacent each reel the upper end of which terminates close to the vessel's side, a lifting wheel rotatably mounted and normally supported in the lower end of each runway and having a swivel attachment whereby it may be connected to the lower 100 end of its respective cable, means for detachably retaining the cable in the said groove during rotation of the reel, and means operative on the vessel's sinking for enabling a grip on the sunken cables to be 105 obtained.

Signed at Vancouver, B. C., this 26th day of September, 1918.

CHARLES E. LONDON.
